ness Machines Corporation, New York, N. Y., a
corporation of New York

Application August 16, 1938, Serial No. 225,086

10 Claims. (Cl. 164—115)

This invention relates to punching machines for punching tabulating cards so that the latter designates certain information.

The improvements relate to an improved means 5 for selecting punches of a punching machine, and constitute, in the present invention a group of relays which are selectively set up to represent data, and which control the selection of punches to punch a card to represent this data.

10 The provision of relays for this type of control enables with facility its incorporation in machines of the electrically controlled type and fits in the scheme of electrical connections and the electrical instrumentalities utilized, so as to 15 provide a simple and efficient means for punch selection.

The main object of the present invention is to provide a set of electrical instrumentalities, such as relays, which are selected from a group to be 20 set up to represent a digit, and then cause the relay just set up to select a punch.

A more specific object of the invention is to provide ten digit representing relays for each order or as an alternative arrangement a lesser 25 number of relays which are set up in combination to represent a digit. In the last arrangement such relays set up contacts in combination and which are interpreted or translated so as to establish a resultant electrical impulse which selects the related punch.

The invention, has for the purpose of illustration, been shown in connection with a tabulating machine and is utilized to cause the punching of group-number-representing perforations. 35 It is proposed in Patent No. 1,946,913 to punch the totals of one or more accumulators on a card and which accumulators receive items entered in a tabulating machine. It has also, heretofore, been proposed as disclosed in Patent No. 1,087,061 40 to utilize one of such accumulators to receive the group number and to cause the punching of the group number under control of the accumulator. The use of such accumulator prevents its customary use as an item receiving accumulator 45 and the provision of the present invention in this arrangement permits, in an admirable way, the utilization of all the accumulators for their customary use.

It is therefore, a more specific object of the 50 present invention to set up on the relays previously referred to in the preceding objects, and by either the arrangement consisting of ten relays for each order or a lesser number of relays set up in combination for each order, the digit 55 representations of the group number, and to

cause these relays to effect the punching of the group number on the card along with the punching of the total thereon.

Another object of the invention is to repeatedly 5 set up the group number by the relays and to break down this setup as long as successive cards agree in their group number representations. The group control sensing means functions to retain this setup so as to cause the relays to select the appropriate punches to punch the 10 group number.

Further objects of the instant invention reside in any novel feature of construction or operation or novel combination of parts present in the embodiment of the invention described and shown 15 in the accompanying drawings whether within or without the scope of the appended claims and irrespective of other specific statements as to the scope of the invention contained herein.

In the drawings:

Fig. 1 is a plan view of the separate punching machine preferably utilized in connection with the present invention.

Fig. 2 is a longitudinal sectional view of the 20 punching machine shown in Fig. 1.

Fig. 3 is a detail view, upon an enlarged scale, 25 showing some of the cooperating parts of the punching machine.

Fig. 4 is an enlarged view in plan of the column selector for the punching means.

Fig. 5 is a view in side elevation of the column selector and is taken on the line 5—5 of Fig. 4.

Figs. 6A and 6B taken together with Fig. 6A on the top is the complete electrical wiring diagram showing the coordination of cooperating 35 parts of the tabulating machine and the perforating machine. The punch selectors, comprising ten relays for each other, as shown in Fig. 6B.

Fig. 6C is a modification of the punch selectors utilizing relays in combinational arrangement, 40 and when substituted for Fig. 6B and placed below Fig. 6A is a completed electrical wiring diagram of the tabulating machine and a perforating machine utilizing this modification.

Fig. 7 is a timing diagram of cams controlling 45 contacts.

Referring to Fig. 1, A indicates generally the column selector attachment of the perforating machine which in conjunction with punch selector relays located in the tabulating machine controls the automatic punching operation and B indicates generally the card punching portion of the perforating machine. The perforating machine without the column selecting attachment is fully described in detail in Patent No. 1,821,078. 50 55

The column selector attachment apparatus is also well known and fully described in Patent No. 2,016,706.

In brief, the operation of the punching mechanism is as follows: A stack of cards to be punched is placed in magazine 10. The operator draws out a rod 11 which feeds one card from the bottom of the stack forward into the punching section provided with a single column of punches 12, each of which is adapted to perforate a corresponding index point position of a card column. To operate the punches manually, the operator depresses a key 13 corresponding to a punch selected for operation. A rod 14 (Figs. 2 and 3) rigidly carried by the key rocks a bell crank 15 counterclockwise which moves an interposer bar 17 to an advanced position over the corresponding punch. As the interposer bar advances, it rocks a bar 18 which is in the path of the interposer bar 17 to the left, which pulls a link 19 (Fig. 3) forward to close contacts 20. Closing of the latter contacts completes a circuit (not shown) through the punching magnet 21 which then attracts armature 22 to pull a rod 610 to rock an arm 24 secured to a rock shaft 600 and thus rock the bail 23 fast to said shaft. Bail 23 is directly over the column of interposer bars 17 and when rocked downwardly depresses the interposer bar which has been advanced by operation of a key 13. The punch 12 corresponding to the depressed interposer bar 17 is thereby operated as is shown in Fig. 3. After each column of the card is punched, an escapement mechanism operates to feed the next card column under the punches 12. The card which is punched rests on a frame plate 620. A card carriage comprising a rack 630 has an arm 640 at the rear carrying a pivoted member 650 which drops behind the rear edge of the card being fed and a hold-down cam gripper 660 (Fig. 2) which engages and holds down the forward end of this card. The rack 630 (Fig. 3) has gear teeth on its lower edge meshing with a gear 670 forming part of the casing of a spring drum enclosing a spiral spring. As the carriage is moved to the right in Fig. 3 the rack rotates gear 670 and tensions the spring drum which thereupon tends to move the carriage back to the left. This movement to the left is controlled by escapement mechanism responsive to the punching operation. A bail 700 is mounted on a shaft 710 and extends beneath all the interposer bars 17 so that when an interposer bar is lowered to effect punching the bail 700 is rocked counterclockwise against the action of a biasing spring (not shown). A pawl 730 is loosely mounted on shaft 710 and a spring 720 attached to an extending arm of the pawl tends to force it into engagement with a series of notches formed on the upper edge of rack 630. A second pawl 800 pivoted on the machine frame, cooperates with pawl 730 to form an escapement. A double arm member 810 is also mounted on shaft 710 and arranged to be operated by bail 700. This member is connected to pawl 800 through a pin 820 on member 810 coaxing with an open slot in pawl 800 and to pawl 730 by means of a pin 750 engaging an enlarged hole in the pawl. Normally when the bail 700 is in raised position the member 810 holds pawl 800 free of the ratchet teeth and holds pawl 730 in engagement with one of them.

On a punching operation the depression of one of the interposers 17 moves bail 700 downward as shown in Fig. 3 and consequently rocks member 810. This first moves pawl 800 into engage-

ment with the ratchet teeth to hold the card carriage against movement temporarily and then owing to the cooperation of pin 750 with the enlarged hole raises the pawl 730 free of the ratchet teeth. The spring 720, on account of the loose mounting of pawl 730, rocks it slightly into position to engage the next ratchet tooth. Then on the raising of bail 700 after the punching in the particular card column has been effected the pawl 800 is raised and the card carriage moves until pawl 730 engages the next ratchet tooth stopping the carriage with the next card column under the punches. This escapement mechanism is fully described in aforesaid Patent No. 1,821,078 and in Patent No. 1,426,223. 10

Those punches whose interposer bars have not been thrust forward will not be affected as their interposer bars will be in the position shown in Fig. 2 with the clearance notches 17a (Fig. 2) under the bail. Contacts 26 (Fig. 2) are provided to cut out the interposer-operating magnets 42, operable alternatively to keys 13, as will be hereinafter explained, while pull-rod 11 is being operated in order to prevent a punching operation during that time (as fully disclosed in aforesaid Patent No. 1,821,078, page 13, line 111 through line 13 of page 14, in conjunction with Figs. 3 and 13).

The automatic control of the punching mechanism includes punch selectors and column selectors. The column selectors are preferably located in the perforating machine while the punch selectors are preferably located in the tabulating machine.

In tabulating machines of the class described the perforated cards are analyzed by a set of upper brushes 60 (Fig. 6A) in one card cycle and then in a subsequent cycle by brushes 61. These two analyzing stations are designated UB and LB in Fig. 6A. A set of lower brushes designated 61a are for the purpose of analyzing amount representing perforations and these amounts are entered in accumulators and when the group number of cards change a perforating machine is adapted to punch on a card the total of such amounts. The arrangement for effecting this function is fully shown and described in the patent to M. Maul, No. 1,946,913. The totals are punched under control of commutators 40a, 40b, 40c, shown in Fig. 6A and fully described in the last-mentioned patent.

It is also desirable to perforate the group number as an incident to perforating the total so that the card punched also bears the group number and later there will be described the means for effecting this function but there will now be described the means for detecting the change in group numbers which causes the automatic initiation of the operation of the perforating machine to perforate the card to represent the total.

The machine successively feeds cards to the analyzing brushes 60 and 61 which read selected group control number representing columns of the cards. The numbers in these selected columns are not accumulated or listed by the machine but serve only as indication or control perforations. So long as the designations in the group control columns of two successive cards agree the machine continues to operate to accumulate and list the items in other card columns. Only two group control columns of the card and two sets of group control elements are shown in Fig. 6A for purposes of illustration but it will be understood that, if desired, use may be 75

made of one, three, four, or more of such columns and corresponding sets of group control elements. Each set of group control elements comprises, aforementioned analyzing brushes 60 and 61 for reading aligned group control number representing columns of upper and lower cards, a magnet 63 connected in series in the same circuit as said brushes, and a pair of contacts 68 controlled by said magnet 63. If the group designations in two successive cards agree the brushes 60 and 61 analyzing the same column of the two cards will contact the perforations in said columns at the same time, thereby completing circuits 62 through magnets 63 which thereupon attract armatures 64 to unlatch bell cranks 65 which are then rocked clockwise by springs 67 to effect closing of contacts 68 there being one pair of coacting contacts 68 operatively associated with each magnet 63. The pairs of contacts 68 are in series in a circuit 69 so that each pair must be closed in order to complete the circuit. This will occur only if the group designations in each column of successive cards agree and some time during the card cycle each magnet 63 has been energized to close the associated pair of contacts 68. Circuit 69 includes a magnet 70 which controls the punch initiating operation. During the perforation analyzing portion of the card cycle, contacts 71 remain closed to complete a circuit 72 through the magnet 70. At the end of the perforation analyzing portion of the cycle, a cam 75 opens contacts 71 but magnet 70 remains energized due to closing of the contacts 68 some time during the analyzing portion of the cycle if the group designations in the cards under the brushes agree.

At the beginning of the next cycle before the successive card is analyzed, cams 66 move bell cranks 65 back into latching engagement with armatures 64 which have, meanwhile, been released by the deenergization of magnets 63. When successive group designations fail to agree, one or more of magnets 63 will fail to be energized and corresponding contacts 68 will thus remain open at and after the end of the analyzing portion of the cycle. After the analyzing portion of the cycle contacts 71 will also open, thus causing the deenergization of a magnet 70 and permitting armature 73, controlled by said magnet, to drop and close contacts 70b. Assuming that switch 76 is closed, the closure of contacts 70b will initiate the punching operation. At the same time that the punching machine control magnet 70 is deenergized under control of the group control device, the latter causes the machine to stop as is well known in the art. The punching of a card in accordance with the total standing on the accumulators thus takes place while the machine is at rest.

As fully explained in Patent No. 1,946,916 when the card to be punched is in punching position for punching the first column, contacts 70b close so as to cause the selection of a punch pin selector magnet 42 under control of commutator 40a to punch the units denomination of the total in the first column, thereafter the card carriage of the perforating machine is stepped so that a contact piece 48 carried by the carriage engages the column contact 46b to cause the selection of a punch magnet 42 under control of commutator 40b to punch the tens denomination, etc. so as to cause successive punching of the digits of the successive denominational orders of the accumulator. When the complete total is punched contact piece 48 will now engage the

column contact 46d to cause punching of the group number by means now to be described.

Referring to Fig. 6B, there will be seen an emitter EM which is in circuit connection with the left line side of the source through a switch 9. The emitter sends successive electrical impulses to a series of ten pick-up relay magnets 31, the wire 33 connecting one side of all of the magnets 31 to the right line side of the source, and the emitter EM is driven by the same shaft 10 in the tabulating machine that drives the dented cam of the circuit breaker 99 shown in Fig. 6A so that impulses are directed to the magnets 31 at the instants the perforations are analyzed, or in other words, the emitter EM has 15 the same timing as the circuit breaker 99.

The pick-up relay magnets 31 attract their armatures 34 and the latter are serially connected by wires 35 connected to the armatures and contacts 40. The wire 33 also connects one 20 side of all the holding relay magnets 32, the other side of each relay magnet 32 leading to a contact 41. As each relay magnet 31 is energized it will attract its armature 34 and the latter will open its contacts 40, if it is so provided with, and close its contacts 41, a circuit 25 now being made from the right line side, wire 33, a relay magnet 32, its contacts 41, its armature 34, and through the wires 35, contacts 40, and armatures 34 of the deenergized magnets 31—30 32 which are lower in serial order, to a wire 43, relay contacts 27, wire 25, cam contacts L—26, and wire 28 to switch 9, to the left line side. Relay contacts 27 are open until a perforation is encountered by one of the lower brushes LB. 35

The arrangement is herein described for only one order, but is disclosed for two orders so as to indicate a group number of two denominations. For the columns of the card which represent the group number the corresponding brushes 61 are 40 plug connected by plug connections 85 (Fig. 6A) to pick-up relay magnets 37, so that when a perforation is encountered the circuit leads from right line side, lower card lever contacts CL, circuit breaker contacts 99 which are closed during 45 the instants the perforations are analyzed, brushes 61, a plug connection 85, relay magnet 37, wire 28, switch 9, to the left line side. When the relay magnet 37 is energized, it attracts its armature to close contacts 27 thus connecting the right line side to a particular holding magnet 32 corresponding to the digit representing perforation analyzed. Relay contacts 27 also close a circuit from the right line side to a holding magnet 38, relay contacts 27, wire 25, cam contacts L—26, wire 28, switch 9 to the left line side. 50 55

When any double wound relay magnet 31—32 is energized it will be seen that the attraction of its armature 34 will disconnect the line 33 from the holding relay magnets 32 lower in serial order, even though the emitter EM causes the energization of the corresponding pick-up relay magnets 31. Hence, it is obvious that the perforations 0—9 will selectively cause the energization of a related holding relay magnet 32. When 65 the zero or any other perforation is analyzed the related pick-up relay magnet 31 will be energized to close contacts 27 and cause the energization of holding relay magnet 38 through the cam contacts L—26 which are also closed when the 70 "0" and other perforations are analyzed.

In the above manner, the pick-up relay magnets 31 and 37 are selectively energized according to the perforations analyzed by the upper brushes and when cam contacts L—26 open the 75

holding circuit through relay contacts 27 is broken and the energized pick-up and holding relay magnets will be deenergized.

As previously stated during operations in which group numbers agree the relay magnet 10 is energized. The relay magnet 10, as shown in Fig. 6B also controls its relay contacts 10a which are in shunt with cam contacts L-26. Obviously, during operations in which group numbers agree relay magnet 10 will keep relay contacts 10a open but upon a change in group number the relay magnet 10 will be deenergized so that relay contacts 10a will close and remain closed. While cam contacts L-26 open it will be seen that the relay contacts 10a will retain the selected holding relay magnets 32 and 38 energized when there is a change in group number.

From the above it is obvious that upon a group change one of the relay magnets 32 will be held energized and the selected relay magnet 32 will cause the closure of its related contacts 81. When the hundreds denomination of the total on the accumulator has been punched the carriage is stepped to now cause the contact piece 48 to engage the column contact 46d thereby causing a punching operation by the following described circuit: The left line side, contact bar 45, contact piece 48, column contact 46d, a wire 82, leading to the common side of a series of contacts 81 of one order, a related wire 84 to the related punch magnet 42, and thence to the right line side, thus causing the selected punch magnet 42 to punch the units denomination of the group number. Thereafter the contact 48 engages the column contact 46e, and by a similar circuit the selected holding relay magnet 32 of the tens order causes the related punch magnet 42 to punch the tens denomination of the group number.

When all of the columns have been punched the skip bar usually provided in machines of the type described will cause the carriage to be skipped to the last column so that the completely punched card may be taken out of the machine.

45 Modification of group punching control using relays

A modification of the group punching control device is disclosed in Fig. 6C and the improved arrangement makes it possible to effect the same results in a simplified manner by the utilization of only five relays per card column.

In Fig. 6C there will be seen four pick-up relay magnets 104, 105, 106 and 107 and by a common wire connection 108 they all have a connection to a socket in which the plug connection 85 of a wire from the related brush 61 is inserted. The other side of each of the relay magnets 104, 105, 106 and 107 is connected to a bus bar 109 through related cam contacts L-33, L-34, L-35, L-36, respectively. The timing of these cam contacts is shown in Fig. 7. The bus bar 109 has a wire connection 110 to the left line side through the switch 9.

65 The perforation in the card connects the right line side to the relay magnets 104-107 by the following circuit, right line side lower card lever contacts CL (Fig. 6A), circuit breaker contacts 99, brush 61, plug connection 85, wire 108 to relay magnets 104-107. The left line side is connected to the relay magnets 104-107 in accordance with the closure of cam contacts L-33, L-34, L-35, L-36 to energize them singly or in combinations. For example, when the "9" perforation is analyzed cam contacts L-33 and L-36 are closed to energize

relay magnets 104, 107. When the "6" perforation is analyzed cam contacts L-34 and L-35 are closed to energize relay magnets 105 and 106.

The holding magnets are designated 111, 112, 113, 114 each of which attracts its armature 116 to close related contacts 117, thereby providing a circuit from the right line side, wire 118, attracted armature 116, related contacts 117 now closed, a wire 120 connecting all of the holding relay magnets, cam contacts L-26 previously described, wire 122, and switch 9 to the left line side. Whenever the relay contacts 117 of the holding magnet 111 are closed a relay magnet 123 is also energized since relay magnet 123 is in shunt with the holding magnet 111.

The cam contacts L-26 function as previously described, that is, to break down any relay magnets that have been energized and the relay contacts 10a previously described have the same function as previously described, that is, to provide a circuit to maintain the selected magnets energized upon a group change. The arrangement for selection of punches is precisely the same as previously disclosed with the exception that the relay magnets 111, 112, 113, 114, and 123 control the opening and closing of their relay contacts, designated with alphabet subscripts and shown at the left in Fig. 6C, singly or in combination to select a punch magnet 42. The following table discloses the various instrumentalities utilized to select punches to punch the digits 0-9.

Punching of digit	Cam contacts	Energized relay magnets	Relay contacts which are operated to effect closure of circuit to select punches
9.....	(L-33..... L-36.....	104-111, 123 107-114	123f. 114b.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In an apparatus for punching information on a record, a plurality of groups of punch selector relays selectively energized and held energized to retain a multi-digit representation concurrently set up thereon, and means controlled by said energized punch selector relays for successively punching digit by digit the multi-digit representation.
2. In an apparatus for punching information on a record, card punches, a plurality of groups of selector relays, card perforation analyzing means, means controlled by said analyzing means

for concurrently energizing and holding energized a plurality of selected selector relays to set up a multi-digit representation, and automatically operated means for initiating the selection of said punches under control of the energized selector relays.

3. In a punching machine, a plurality of denominational ordered groups of punch selector relays, means for concurrently energizing said punch selector relays in said groups for setting up data thereon, means controlled by said relays for punching the data set up thereon digit by digit, and means for causing the de-energization of the energized punch selector relays concurrently in the plurality of groups of selector relays.

4. In a punching machine, a plurality of denominational ordered groups of punch selector relays, means for analyzing data representing perforations in a record, means controlled by said analyzing means for concurrently and selectively energizing said groups of punch selector relays to set up thereon corresponding data, a punching means including punches, and means for causing the energized relays of said groups to successively select said punches for perforating a record sheet to represent said data.

5. In a machine for perforating cards, a plurality of punch selector relays, electrical contacts controlled thereby, means for analyzing digit representing perforations, contact making means for transmitting impulses to said relays singly or in combination, means controlled by said analyzing means for rendering said contact making means effective to cause the energization of said relays to set up said contacts in combination, means for translating the meaning of said contacts set up in combination and deriving therefrom a single electrical timed impulse, and means for causing the timed electrical impulses to select said punches.

6. In a punching machine, a plurality of denominational ordered groups of punch selector relays, means for analyzing group number representing perforations of successive groups of cards, means controlled by said analyzing means for selectively energizing said relays to represent the group number, a punching means comprising punches selected by said punch selector relays, and means responsive to a change in group number of said cards for causing said punch selector relays to select said punches for a punching op-

eration for perforating a sheet to represent the group number.

7. In a punching machine, a plurality of denominational ordered groups of punch selector relays, record controlled means for concurrently and selectively energizing said groups of punch selector relays, means for holding said energized relays in energized condition, punching means including punches, means for causing said energized relays to select in succession said punches to punch information digit by digit, and means for rendering said holding means ineffective at the completion of the successive punching operation.

8. In a device for controlling punches of a punching machine by a tabulating machine comprising a plurality of groups of selector relays energized and held energized to retain a setup thereon to represent data corresponding to groups of cards controlling said tabulating machine, punches of said punching machine selected by said selector relays, means responsive to a change in designations of card groups for automatically initiating the operation of the punching machine and for causing said energized selector relays to select said punches.

9. In a device for controlling punches of a punching machine comprising a plurality of groups of punch selector relays, means for energizing said relays to set up data thereon corresponding to data represented by groups of cards and for deenergizing said energized relays as long as said data remains unchanged for a group of cards, and sensing means for detecting a change in card groups for causing the energizing punch selector relays to remain energized to select said punches of the punching machine.

10. In a device for controlling punches of a punching machine to successively punch the denominational orders of a column of a record sheet, a plurality of groups of punch selector relays, means for energizing said punch selector relays in accordance with group number data on successive cards and including means for deenergizing said energized punch selector relays as long as said group number data on successive cards agree, group number change sensing means, and means controlled by said sensing means for retaining the energization of said punch selector relays to control the selection of punches of said punching machine.

GOINO GHERTMAN.
